UNITED STATES PATENT OFFICE.

FRANZ SCHERRER, OF BONN, GERMANY.

LADDER FOR LIFE-SAVING.

SPECIFICATION forming part of Letters Patent No. 743,199, dated November 3, 1903.

Application filed May 2, 1903. Serial No. 155,324. (No model.)

To all whom it may concern:

Be it known that I, FRANZ SCHERRER, a subject of the King of Prussia, German Emperor, residing at Bonn-on-the-Rhine, in the Province of the Rhine, Kingdom of Prussia, German Empire, have invented a new and useful Ladder for Life-Saving, of which the following is a specification.

My invention relates to ladders for life-saving, and more especially to ladders of the kind described in the specification of German Patent No. 129,205. Ladders of this kind are composed of two different classes of small ladders, which I shall call "unmovable" ladders and "movable" ladders, respectively. The unmoving ladders are rigidly attached to a vertical shaft passing along all the windows of the same vertical row, while the movable ladders are arranged to move up and down. When the ladder is out of use, the movable ladders are drawn upward, so as to lie parallel to the unmoving ladders fixed to the vertical shaft, which has such a position that the whole device is, as it were, concealed in the recesses formed by the windows. For bringing the ladder in use the vertical shaft is turned on an angle of ninety degrees. The movable ladders being then no longer supported will drop down, thus connecting the ends of the unmoving ladders, and the whole ladder takes up a position rectangular to the front of the building.

My invention consists in rigidly attaching rack-bars to the sides of the movable ladders and in providing pinions gearing with the said rack-bars and means for actuating such pinions. By this means the movable ladders can be instantly drawn upward when the whole ladder has been used for exercising purposes, and they can be forcibly moved downward if they are by accident hindered from dropping automatically.

I refer to the drawings, in which—

Figure 1 is an elevation of the whole ladder in use, the adjacent portion of the building being shown in section. Fig. 2 is a vertical section on line A B of Fig. 1. Fig. 3 is an elevation of a modified construction likewise in use. Fig. 4 is a vertical section on line C D of Fig. 3. Fig. 5 shows a portion of Fig. 3 on a larger scale.

As to Figs. 1 and 2, *a* is the vertical shaft

passing along all the windows of the same vertical row. Rigidly fastened to the said shaft *a* are frames *b*, which at their outer ends are formed to serve as the movable ladders mentioned above. The sides *c d* of the ladder are channel-irons for guiding the sides *f g* of the movable ladders, respectively. The inner sides *f* are provided with rack-bars *h*, gearing with pinions *i*, which are fixed to the outer ends of spindles *k*. The latter have handles *m* for allowing of turning the spindles, together with the pinions *i*, in order to move the small ladders *f g* up or down. The horizontal toothed wheels *n* of conical shape fixed to the vertical shaft and the vertical toothed wheels *o* gearing with the former and adapted to be rotated by hand serve for turning the shaft *a* on an angle of ninety degrees, as described in the specification of German Patent No. 129,205.

As to the modification shown in Figs. 3, 4, and 5, the vertical wheels *o* mesh with horizontal wheels *p*, loosely mounted on the shaft *a*. Below each frame *b* three gearing-wheels *q r*, and *s* are journaled in an arm *t*, rigidly fastened to the frame, and the lowest of the said wheels *q* carries a conical wheel *u*, which gears with the conical wheel *p*. The wheels *s* are fixed to the inner ends of the spindles *k*, the handles *m* of the latter being of course dispensed with. It will be seen that on rotating the vertical shaft *a* the movable ladders will be forcibly and automatically raised or lowered, according to the sense of rotation.

What I claim as my invention, and desire to secure by Letters Patent of the United States, is—

1. In a life-saving apparatus the combination with a vertical shaft passing along all windows in the same vertical row, means for rotating the said vertical shaft, ladders rigidly attached to the same and movable ladders for connecting the former ladders when in use, of rack-bars fastened to the movable ladders, pinions gearing with the said rack-bars, and means for rotating the said pinions, substantially as and for the purpose set forth.

2. In a life-saving apparatus the combination with a vertical shaft passing along all windows of the same vertical row, means for rotating the said vertical shaft, ladders rigidly attached to the same and movable lad-

ders for connecting the former ladders when in use, of rack-bars fastened to the movable ladders, pinions gearing with the said rack-bars, a gearing mechanism between the said 5 pinions and the means for rotating the vertical shaft mentioned above, substantially as and for the purpose set forth.

In testimony whereof I have signed my name to this specification in the presence of two subscribing witnesses.

FRANZ SCHERRER.
